UNITED STATES PATENT OFFICE.

IRA W. NOYES, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed May 1, 1928. Serial No. 274,240.

This invention relates to warp stop mechanisms for looms and is more particularly directed to warp stop mechanisms of the transversely movable toothed detector bar 5 type wherein the detector bar is given its transverse movements from the actuator through a link connection therewith.

It is now the ordinary practice to provide a link connection between the actuator and 10 the transversely movable detector bar, and the link is usually pivoted to the actuator and has an open slot in its opposite end for engagement with a pin or projection extending laterally from the transversely movable 15 actuator bar.

It frequently happens during weaving or manipulation of the loom by the attendant, that one or more of the detecting bars may become accidentally detached from its link 20 connection with its actuator, because the link is connected to the detector bar by an open slot and may be readily, through accident or otherwise, detached therefrom. Should this occur and the loom be started, the detector bar thus detached from its actuator 25 would fail to function, with the result that no detection of the warp fault in the series of drop wires associated with such detector bar would occur, and imperfect cloth is liable 30 to be woven.

One of the important features of the present invention therefore consists in providing a simple yet effective lock for securing the detector bar to the link connection between 35 it and its actuator, so that accidental detachment of the link from the detector bar is rendered impossible, or substantially so.

The invention and novel features thereof 40 will best be made clear from the following description and the accompanying drawings of one good form thereof.

In the drawings:

Fig. 1 is a side elevation of one end of a warp stop mechanism containing the present 45 invention;

Fig. 2 is an enlarged perspective view of disassembled parts which more particularly include the present invention;

Fig. 3 is an enlarged side elevation showing the detector bar and link connected together; and

Fig. 4 is a section on the line 4-4 of Fig. 1.

The locking connection between the transversely movable detector bar and its actuator

may be advantageously employed in any usual form of warp stop mechanism wherein a transversely movable toothed detector bar is employed, but, as illustrated in Fig. 1, for illustrative purposes, the warp stop mechanism is of the general type shown in the patent to Davis and Johnson, No. 1,538,625, dated May 19, 1925.

As more fully described in the above-mentioned patent, the warp stop mechanism comprises the usual end supports 1, one at each side of the loom, between which extend the warp rests and spacing bars 2.

Mounted in a bracket 3 extending from one of the side supports or brackets 1 is the rock shaft 4 to which is connected the arm 5 which may be actuated through a link 6 and arm 7 from any convenient going part of the loom, as, for instance, a cam on the lower or cam shaft, as usual. Mounted for movement with the rock shaft 4 is the rocker 8, of which there may be any suitable number corresponding to the number of banks of drop wires employed, and mounted upon each of the rockers 8 is an actuator 9 having pins 10 which rest in seats in the rockers 8 under the influence of a spring 11 normally acting as set forth and more fully described in the patent to which attention has been directed, to maintain the 70 actuators and rockers in operative relation, and yet permit the actuator to come to rest when the transversely movable toothed detector bar to which it is connected is arrested 75 on the occurrence of a warp fault.

Pivottally mounted on the rocker at 12 is a finger 13 connected at 14 to the associated actuator 9, the construction being such that should the actuator 9 be arrested while the rocker continues to move, the outer end portion of the finger 13 will be depressed and act through a train of mechanism to effect loom stoppage. In the present instance of the invention, the finger 13 acts upon an arm 15 which rests upon the upper end portion of a plunger 16 associated with a flexible sheathed wire 17 which, upon the occurrence of a warp fault, is moved longitudinally in its sheath, as more fully explained in the Davis and Johnson patent, to effect 100 loom stoppage. It is not deemed necessary herein to further describe the particulars of the warp stop mechanism in detail, since these are all fully described in said patent, and the details of such mechanism constitut- 105 110

ing the main portions of the warp stop mechanism form no essential part of the present invention.

Extending between the side brackets or supports 1 of the warp stop mechanism is the transversely movable toothed detector bar 18 having the teeth 19, and associated with the movable detector bar is the relatively fixed toothed detector bar 20 which may be conveniently supported in the upper portion of the side brackets 1, as more fully described in the above-mentioned patent and as generally indicated at 21, Fig. 1.

In the present instance of the invention, the fixed toothed detector bar 20 is provided with a groove 22 extending longitudinally thereof, in which the movable detector bar 18 slides.

The movable detector bar 18 is provided with a pin 23 which passes through a slot 24 formed in the fixed detector bar 20, and the end portion 25 of the pin is threaded and passed through an opening 26 in the movable detector bar 18 where the threaded end of the pin is secured in place by a nut 27.

The pin 23 has a barrel portion 28 which projects at one side of the movable toothed detector bar 18, and mounted on the barrel portion 28 of the pin is the split sleeve 29 which may be slightly less in width than the barrel portion 28 of the pin, so that the stress of the nut 27 will maintain the end portion of the barrel 28 in binding engagement with the side of the movable detector bar 18 without at the same time interfering with the spring qualities of the split spring sleeve 29.

As hereinbefore indicated, the movable toothed detector bar 18 is connected to its associated actuator by a link, which, in the present instance of the invention, is provided with an opening 30, by which the link 31 is pivotally connected to its actuator 9.

The downturned end portion 32 of the link 31 is provided with an opening 33, the entrance to which at 34 is of less width than the dimensions of the split sleeve 29, with the result that when the open end portion of the link 31 is forced into engagement with the split sleeve, the latter will be compressed in opposition to its spring qualities, and then slightly expand as the opening 33 of the link finally embraces the split sleeve and effects a union between the link and the transversely movable toothed detector bar.

When the parts are in assembled relation, as indicated in Fig. 3, the link is yieldingly locked to the transversely movable toothed detector bar 18, and to disengage the link from the detector bar considerable intentional force must be exerted on the link, the result being that accidental or unintentional disengagement of the link from the movable toothed detector bar is rendered substantially impossible.

When the parts are to be assembled, as indicated in Fig. 3, the pin 23 is secured to the movable toothed detector bar 18 by the nut 27 which engages the threaded end 25 of the pin, and the inner shoulder portion of the barrel 28 rests against the side of the toothed detector bar, as indicated in Fig. 4, thus leaving the split spring sleeve 29 free to the influence of its spring action, and yet compressible against such action as the narrow entrance 34 of the link 31 is forced downward over the split sleeve. When the parts are in assembled relation, the split spring sleeve serves to effectively lock the link and movable toothed detector bar in their associated relation and effectively prevent any accidental disengagement of the two, thereby insuring against the weaving of imperfect cloth. Should it be desired at any time to disconnect the link from its associated relation with the movable toothed detector bar, this result may be effected by a forceful manual movement of the link, which thereupon compresses the split spring sleeve as the narrow entrance 34 of the open slot 90 passes from engagement therewith.

It will be understood, of course, that the detector bars have associated therewith the usual drop wires 35 which are normally supported by the warp threads during weaving and effect loom stoppage on the occurrence of a warp fault, and, of course, any number of banks of drop wires and associated detector bars may be employed.

What is claimed is:

1. In a warp stop mechanism for looms, the combination of drop wires, a transversely movable toothed detector bar having a pin secured thereto and a spring sleeve mounted on the pin and compressible in a direction to decrease its diameter, an actuator for the transversely movable detector bar, a link connected to the actuator at one end and having an open slot adapted to receive the spring sleeve and provided with a contracted entrance at its other end for compressing the spring sleeve as the link and pin are manually engaged.

2. In a warp stop mechanism for looms, the combination of drop wires, a transversely movable toothed detector bar, an actuator, a link for connecting the actuator and toothed detector bar having an open slot, and a manually operable lock between the link and detector bar, comprising a pin secured to the detector bar, a split spring sleeve mounted on the pin and normally of greater size than the open slot of the link that the detector bar and link may be manually locked and unlocked by forcing the opening into and out of embracing engagement with the sleeve.

3. In a warp stop mechanism for looms, the combination of drop wires, a transversely movable toothed detector bar, an

actuator for said bar, a link pivoted at one end to the actuator and having an opening with a contracted entrance at the other end, a pin of less size than the contracted opening of the link, and a split spring sleeve of larger size than the entrance to said opening mounted on the pin and constituting a manually operable lock for connecting and disconnecting the toothed detector bar with its actuator.

4. In a warp stop mechanism for looms, the combination of drop wires, a transversely movable toothed detector bar, a pin secured thereto and having a barrel portion at one side of the detector bar, a split spring sleeve mounted on the barrel portion of the pin, an actuator for the transversely movable detector bar, a link pivotally connected to the actuator and having an opening provided with an entrance of less di-

mension than the split spring sleeve that the latter may be compressed as the detector bar and link are manually engaged and disengaged.

5. In a warp stop mechanism for looms, 25 the combination of drop wires, a transversely movable toothed detector bar and its actuator, a link pivoted to one of said parts and having an open slot in its opposite end, a pin extended from the other of said parts 30 having a barrel portion and a split spring sleeve thereon adapted to be embraced by said slot but having a larger dimension than the entrance to said slot and constituting a yielding and manually operable lock for 35 connecting the link and pin.

In testimony whereof, I have signed my name to this specification.

IRA W. NOYES.
